SHIPPING ENCLOSURES

Doyle M. Weaver, South Gate, and Kenneth Atchison, Garden Grove, Calif., assignors to The Flintkote Company, New York, N.Y., a corporation of Massachusetts

Filed July 15, 1963, Ser. No. 295,089

3 Claims. (Cl. 206—46)

This invention resides in a carton-like structure which replaces the outmoded crates conventionally used for the shipping and storing of large, heavy fixtures such as bathtubs.

Although this discussion of the invention is addressed mainly to the handling of bathtubs—as this is the area in which it was developed—the invention may be applicable to other areas in which the same basic considerations apply. The commonly known commercial varieties of pressed steel and cast iron bathtubs possess a combination of characteristics which require that special attention be given to preparing these items for shipping, storage and other handling. Among these characteristics are large size, somewhat irregular shape, a vitreous surface susceptible to damage, and weight typically in the range of 150 to 400 pounds. Whatever the means employed for packing, crating or other protective covering, its acceptability for use will depend on various factors such as: direct unit cost, ease of set-up and assembly, effectiveness in protecting fixtures against damage by rough handling, durability of the protective covering itself under rough handling and outdoor storage, and finally, the matter whether it hinders or facilitates the handling of fixtures.

In the past, fixtures such as bathtubs have been shipped almost exclusively in crates formed of wood slats held together by bailing wire and staples. For such purposes crates are objectionable in several respects. Principal disadvantages of crates are their relatively high unit cost and the fact that they are cumbersome to store and handle and to set-up around a bathtub. A further disadvantage is that due to the jagged surface presented by a slatted construction, a crated bathtub is not as easily moved about as one encased in a smooth, carton-like structure. Finally, it generally is desirable to provide substantial spaces on the exterior surface for the purpose of printing informative or promotional matter, and typical crates do not have such adequate space.

Accordingly, it is the principal object of this invention to provide basically improved means for enclosing, protecting and facilitating the handling of fixtures such as bathtubs.

More specifically, it is the principal object of this invention to provide an enclosing structure which combines all of the following advantages: low cost; convenience and ease of storing, handling and assembly; adaptability to semi-automatic assembly; effectiveness in protecting the fixture; durability under both rough handling and exposure to the elements; a smooth, neat exterior design for ease of handling; large areas provided for printed matter; and ease of disassembly.

Briefly, these objects are attained in a carton-like structure comprising as its basic parts a pair of covers spanning the entire upper and lower parts of the tub, a pair of frames which are self-interlocking both with these covers and with the respective ends of tubs, and simple metal strapping binding these parts. Each of these end frames is so constructed that, in being "interlocked" with an end of a bathtub, it derives its outward rigid strength from the inherent strength and support of the fixture which it serves to protect.

A great contribution to the overall combination of advantages is made by the upper and lower covers, which

2

initially are low cost, flat carton blanks. Each cover incorporates a novel construction whereby it can be set-up quickly and easily and without the need of supplemental fastening means. Specifically, the cover has sides, formed by folding of the blank, which assist in positioning of the end frames while also positioning the cover over the bathtub. A significant feature is that the shape of the cover after setting up is maintained by a novel tab construction to be described hereafter.

In summation, the invention to be described hereafter attains all of the objectives set forth above. Further objects, advantages and details will become evident from this description, which is to be read in conjunction with the accompanying drawings, in which:

FIGURE 1 is a perspective view showing a bathtub in association with the principal parts of the enclosing structure in a state of disassembly;

FIGURE 2 is a perspective view of the finished assembly;

FIGURE 3 is a view of the inner side of one of the end frames;

FIGURE 4 is a transverse section through the finished assembly, taken as indicated by lines 4—4 in FIGURE 2;

FIGURE 5 is a longitudinal sectional view taken as indicated by lines 5—5 in FIGURE 4;

FIGURE 6 is an illustration of the outer side of the cover carton blank prior to set-up; and

FIGURE 7 is a perspective view of the inside of the cover after it has been set-up.

The principal parts comprising this invention are a pair of identical carton-like covers 2 and a pair of frames 4 that are identical except for one detail mentioned hereafter. A typical bathtub of the "built in" style is designated "B" and some details thereof will be pointed out as a preliminary to description of the other parts. The bathtub has a skirt 6 at only the front side, though in some types the skirt extends around one or both ends. (The type illustrated will be recognized as one in which the rearward side and both ends abut a wall.) The skirt 6 has an inwardly turned foot portion 8 intended to rest on the floor, and welded straps 10 serve as bracing of the skirt 6 to prevent fracture thereof from the main body portion. Around the entire periphery of the tub there extends outwardly a rim or flange 12 which, together with the side edges of skirt 6, is significantly utilized in connection with bracing and locking of the end frames 4. Welded to the rearward sides of the tub are brackets 14 by means of which the tub is secured to the wall.

The structure of the end frames 4 is best seen in FIGURES 1 and 3. A rectangular frame is constructed by nailing or stapling top and bottom members 16 and 18, respectively (the "top" and "bottom" being as viewed in these drawings), together with back and front side members 20 and 22, respectively. At one side of this frame, upper and lower panels 24 and 26, respectively, are similarly secured by nailing or stapling and serve both as bracing and as a means helping to position the frame on the tub as described hereafter. The members 16, 18, 20 and 22 can be cut from ordinary wood stock or plywood having a thickness in the range of one half inch to one inch. The panels 24 and 26 preferably are plywood having a thickness of $\frac{1}{8}$ to $\frac{3}{8}$ inch. On the inner side of the lower panel 26 there is secured a strip of wood 28 having a thickness (extending outwardly away from panel 26) of one half inch or more and spaced from the lower frame member 18 by a distance "d" which is only slightly greater than the thickness "t" of flange 12. (In fact, distance "d" may be the same as or slightly less than thickness "t" so that the groove defined between yieldable members 28 and 18 must be forced over the rigid flange 12 in the course of assembly.) It has been found that the wooden parts of the frames preferably are fastened by

means of special resin-coated staples, of a type well known in the art, which resist pulling out under severe handling. It will be noted that, as viewed in FIGURE 3, the right end of strip 28 terminates a distance away from the member 22 that is intended to engage the front skirt 6 of the bathtub. The frames 4 used at opposite ends of the tub differ only in the placement of strip 28, and in effect they are mirror images of each other. In each case the strip 28 merely is fastened closest to the member 20 that is to be at the rearward side of the tub.

As evident in FIGURE 4 in particular, the inner dimensions of a frame 4 closely fit the maximum dimensions of the tub B. Movement of each end frame inwardly over the end is limited by engagement of panel 24 against the end of skirt 6 and its foot portion 8, and by the engagement of panel 26 against flanges 12. Relative shifting and twisting either vertically or horizontally (in a plane transverse to the length of the tub) is limited by the close fit of side members 16, 18, 20 and 22 around the tub. Finally, the flange 12 is firmly held between strip 28 and member 18, so that if the entire assembly is turned upside-down the flange 12 will exert weight on strip 28 instead of member 18 and shifting the tub relative to frame 4 thereby will be prevented.

Referring next to FIGURE 6, there is shown a carton blank having a large, rectangular central area 40. This blank is cut from corrugated paper board which has been impregnated with a special asphalt composition and manufactured with water-resistant adhesives, making it highly resistant to water and other agents which normally might be encountered in the course of shipping and storage. Two end panels 42 are formed by folding along serrated lines 44. Cuts 46 extend inwardly in alignment with lines 44 to the extent of further serrated fold lines 50 to define tabs 48. At the side of the blank there are serrated fold lines 52 and 54 which form side panels 56 and 58, each of which has a width approximating the width of an end panel 42. Thus, by folding twice, along lines 52 and 54, a panel 58 is folded backwardly over its associated panel 56. Prior to this step, however, the end panels 42 are folded inwardly and tabs 48 are bent as shown in FIGURE 7, whereby these tabs become interleaved and locked between a pair of backwardly lapped side panels 56 and 58. In setting up the covers 2, a significant saving of time and steps is effected by the simple manner in which the side panels 56 and 58 are retained in their folded condition. This feature comprises flaps or tabs 60 defined by cuts in the carbon blank at locations directly adjacent fold line 52. Each tab 60 extends in a direction parallel to line 52, whereby it can exert considerable resistance in a direction against the face of a side panel 58. Thus, by the simple expedient of deflecting the tabs 60 inwardly, after end panel 42 and side panels 56 and 58 have been properly folded the cover is retained in its set-up condition.

The novel construction of cover 2 lends itself to semi-automated or fully automated assembly, though the means therefor are not disclosed herein and form no part of the present invention.

Cover 2 preferably is provided at its corners with printed strap guides 62 over which a metal strapping or band 64 is placed to bind and secure the final assembly.

In practice, there are various approaches that can be taken to enclose a bathtub with the carton-like frame and cover structure according to this invention. Generally, both end frames 4 will be put in place first and then the pre-assembled covers 2 will be placed over them and the tub. For example, in a simple assembly procedure, with the tub resting flatly in either its normal or inverted position the end frames are slipped on to the tub ends and fitted thereon as previously described. A fully set-up cover 2 can then be positioned over the tub and the tops of the end frames 4, and the entire assembly is then turned

over to the opposite side to permit the placement of a second cover 2 thereon. After both covers thusly have been placed, metal strapping or band 64 is passed around the ends directly over the edges of frame 4, i.e., at the location of printed strap guides 62, and clinched at 66 (FIGURE 4) by means of a standard device well known in the art. The enclosure of the bathtub has now been fully completed.

It will be recognized that because of the smooth, straight lines of the tub enclosure described above, stacking, sliding, turning, and other movement in handling are simplified. The costs of materials and of labor involved in assembly are considerably less per unit than with crates, for example. The bathtub can be quickly enclosed on a mass production basis due to the simplicity of the end frames and covers. Maximum protection of the fixture is afforded where most needed, namely, at its ends. The double thickness of panels 56 and 58 also serves as extra padding for protection of the bathtub corners. The components are durable under rough handling and resistant to adverse conditions in shipping and storage. The process of disassembly is equally as simple as the assembly operation. Finally, the finished product presents a pleasing appearance and adequate space for printing of informative or promotional material.

It will be understood that various departures from the specifically disclosed embodiments of this invention can be effected without departing from the scope thereof as defined by the following claims.

What is claimed is:

1. A package comprising, in combination, a large plumbing fixture; a pair of rigid rectangular frames directly fitted upon the ends only of said fixture; and a pair of covers each of which comprises a rectangular main wall having a plurality of inwardly extending finger-like tabs adjacent the side edges thereof, a pair of perpendicularly extending two-ply side walls attached to said main wall and being formed by folding a panel over itself into overlapped relation with the free edge of said panel being engaged by said tabs to maintain said side walls in a position perpendicular to said main wall, a pair of perpendicularly extending end walls attached to said main wall, and a pair of locking flaps attached to the side edges of each of said end walls, said locking flaps being perpendicular to said end walls and being located between the plys of said side walls to maintain said side walls in a position perpendicular to said main wall; the main panels of said covers overlying opposite faces of said fixtures, and the inwardly directed corners of said covers receiving and engaging the corners of said frames.

2. In the combination according to claim 1 wherein said fixture has a protruding peripheral flange at each end and each of said frames has a complementary groove therein which receives and grasps the related flanges.

3. In the combination according to claim 2, and further comprising a metal band encircling said covers and frame at each end to tightly bind the elements of said package together.
